WALL BRACKET FOR A TELEPHONE, MEMO PAD, AND PENCIL

Robert J. Waxman, Elkins Park, and John W. Walters,
Willow Grove, Pa.

Application December 27, 1955, Serial No. 39,493

Term of patent 3½ years

(Cl. D26—14)

FIG. 1

FIG. 2

Fig. 1 is a front elevational view of a wall bracket for a telephone, memo pad and pencil showing our new design; and

Fig. 2 is a front perspective view thereof.

The dotted line illustrations of the pad and pencil shown in Fig. 2 are for illustrative purposes only. The back of the wall bracket is plain and unornamented.

We claim:

The ornamental design for a wall bracket for a telephone, memo pad and pencil, as shown and described.
